UNITED STATES PATENT OFFICE.

HERBERT TALLEY, OF JOPLIN, MISSOURI, ASSIGNOR, BY MESNE ASSIGNMENTS, TO
HERCULES POWDER COMPANY, A CORPORATION OF DELAWARE.

SHELL FILLING AND CLOSING MACHINE.

1,245,528.

Specification of Letters Patent. Patented Nov. 6, 1917.

Application filed April 19, 1912. Serial No. 691,825.

To all whom it may concern:

Be it known that I, HERBERT TALLEY, a citizen of the United States, residing at Joplin, county of Jasper, and State of Missouri, have invented certain new and useful Improvements in Shell-Filling and Closing Machines, of which the following is a specification.

This invention relates to shell filling and 10 closing machines.

The present invention has for one of its objects the provision of a machine which will automatically assemble and place empty shells in a shell holder and will automatically 15 load the shells thus placed with explosive or other material; further, a machine which will close the filled shells; still further, eject the filled and closed shells.

Another object of the invention is the 20 provision of shell holding means and a movable explosive feeding mechanism adapted to be positioned for the delivery of the explosive to the shells and having means for then forcing the explosive into the shells.

25 This feeding mechanism is operated by motive fluid pressure. This feeding mechanism has a system of, and means for, control of, the motive fluid pressure, whereby the feeding mechanism is placed in position for 30 loading the shells by a more or less gradual movement as contradistinguished from a quick or abrupt movement, and, further, the extrusion or forcing of the explosive into the shells is initiated and continued in an 35 even and regular, but not abrupt, fashion, whereby too sudden or undue pressure on the explosive is prevented; further, this control system causes quick return of the parts of the feeding mechanism to normal po- 40 sition.

The feeding mechanism of the present invention and the controlling means therefor are especially advantageously employed in connection with the shell holding means. 45 Heretofore it has been proposed to move the shell holder or carrier into position in relation to the feeding means. In my machine, however, the shell holder is not moved toward and away from the feeding mechanism and hence is rendered especially adaptable for the utilization of my new shell assembling or placing mechanism, and shell closing mechanism, these last-named mechanisms being rendered adaptable for opera- 50 tion and control by motive fluid pressure

system aforesaid, the shell closing mechanism being prevented from too quick or abrupt operation when closing the shells, and the shell assembling and placing mechanism prevented from too rapid assembly or 60 placing of the shells.

The motive fluid pressure operated shell closing mechanism is automatically controlled in such manner that, while quickly operated, its operation is not too abrupt or 65 attendant with danger of undue pressure on the filled shells.

In the present invention, the shell holders, shuttles or carriers, are mounted in a rotating series and turned, step by step, by novel 70 motive fluid pressure operated mechanism, doing away with the necessity for turning the shell carrier by hand. This mechanism turns, checks, and locks the system of shell carriers so that they will be accurately positioned for assembly of the empty shells, filling thereof and closing, as also for discharge of the loaded and closed shells. 75

The shell assembling or placing mechanism is claimed in the present application 80 only in its combination with and use on the present machine. Such shell placing or assembling mechanism constitutes the subject-matter of another application which has matured into Patent No. 1,105,936, dated 85 Aug. 4, 1914.

The shell holding shuttles are claimed in this application only in combination with the present machine. The shell holding shuttle and the shuttle carrier set forth herein 90 in each constitutes an independent invention susceptible of use on other machines and its subject-matter is set forth in another application, which has matured into Patent No. 95 1,105,936, dated Aug. 4, 1914.

The invention also consists in the complete automatic motive fluid pressure system of operation and control for the feeding mechanism, the shell assembling and placing means, and the shell closing means, 100 but it is not restricted to the complete motive fluid pressure operating and controlling system, as different parts and mechanisms thereof are new in and of themselves and constitute separate inventive features 105 thereof.

The explosive feeding mechanism and its automatically acting system for supplying and controlling motive fluid pressure to position the parts for initiating, carrying on 110

and completing the loading operation constitutes one feature of the invention; the shell assembling and placing mechanism in connection with the operating and controlling system for the feeder constitutes another part of the invention; the automatic assembling and placing of the empty shells and the automatic closing of previously loaded shells, in conjunction, constitutes a third feature of the invention; the conjoint operation and control of the explosive feeder, the shell assembler, and the shell closer by the same motive fluid pressure operated system constitutes a fourth part of the invention.

The above enumeration of objects and nature of the invention is not to be considered as restrictive of its scope, but as illustrative thereof.

20 In the accompanying drawings:

Figure 1 is an elevation;

Fig. 2, an elevation taken at the left of Fig. 1, certain parts being in section and broken away;

25 Fig. 3, a section on line 3—3, Fig. 1;

Fig. 4, a diagrammatic view of the different mechanisms and the fluid pressure operating system therefor;

Fig. 16, an end view of the shuttle;

Fig. 17, a horizontal section through two 55 of the leaves showing the springs which open them;

Fig. 18, a detail perspective view of a leaf of a shuttle;

Fig. 19, a side elevation of the shell carrier and the shuttles, certain parts being in 60 section;

Fig. 20, a detail diagrammatic view of the shell carrier showing the weights which coöperate with the different shuttles; and

65 Fig. 21, a detail perspective view of the weights of Fig. 20.

The frame consists mainly of uprights 1 and a yoke 2. Slidable on the uprights 1 is a carriage 3, the lower part of which carries a feed hopper 4 which has an extended or elongated mouth 5 so that the explosive 70 can be fed thereto and a quantity be ready for admission to the hopper as the piston makes its successive strokes. Attached to the bottom of the hopper 4 are nipples or nozzles 6. These are preferably carried by 75 a single removable end or head which is detachably connected to the lower end of the hopper. These nipples are adapted for insertion into the paper shells which are commonly employed for containing the gelatin 80 dynamite which the machine is adapted to load. The nipples 6 are grouped in as great a number as desired, the number corresponding to the number of shells adapted to be held by the shell holder or shuttle and to the 85 position of the shells therein.

The cylinder 7 is carried by carriage 3. Operable therein is a piston 8 whose rod or plunger 9 carries a forcing piston or plunger 10 adapted to operate in the hopper 90 4 and to fit it. As the piston or plunger 10 advances in the hopper 4, it forces the plastic explosive gelatin dynamite out through the nipples or nozzles 6 and into the shells. The piston or plunger rod 9 95 carries a cross-head 11 which is slidable on the sleeves of carriage 3, the said cross-head and piston being adapted to move in relation to the carriage independently of the movement of the carriage up or down on the 100 uprights 1.

To assist the motive fluid pressure operating and controlling mechanisms herein-after described in giving an even and regular rather than an abrupt movement to the 105 piston 8, particularly in its downward stroke when loading the shells, there are provided cylinders 12 containing oil in which pistons 13 are adapted to move, said pistons being connected by rods 14 to the cross-head 11. 110 The pistons 13 have a loose fit in the cylinders 12 so that the oil contained in the cylinders 12 may gradually flow from one side of the piston to the other, this arrangement constituting an oil check which-ever way the piston 8 is moving. To equalize the flow of the oil and the resistance of the pistons 13, the cylinders 12 may be connected by a pipe 15.

Carried by the yoke 2, is an operating 120 cylinder 16 in which moves a piston 17 whose piston rod 18 is connected to the carriage 3 in any suitable manner, the piston rods 9 and 18 being preferably in alinement. Oil checks embodying cylinders 19, pistons 125 20 and rods 21 connecting said pistons 20 to the carriage 3, serve as an oil check to prevent too abrupt upward or downward movements of the carriage 3 by the piston 17 and its rod 18.

The piston 17 is adapted to move the carriage 3 downwardly to position the nipples 6 in the shells prior to the extrusion of the explosive gelatin from the hopper 4 by the piston 10 which is operated by piston 8.

Preferably the carriage 3 and all parts carried thereby are counterpoised, so as to minimize the air or other motive fluid pressure required to operate them. Such counterweighting may be conveniently accomplished by providing a shaft 22 secured to or mounted on the uprights 1 and secured to or mounted on said shafts are sheaves 23 over which run cables 24 connected to the carriage 3 and provided with a suitable weight 25.

Rotatably mounted in or on the uprights 1 is a shell carrier 26 which is adapted for rotation to move the shell holders or shuttles 27 to their different positions. The shell carrier is adapted to rotate step by step to permit the simultaneous, or substantially so, placing of empty shells in one shuttle 27, the filling or loading of the shells in another shuttle 27, the closing of previously filled shells in another shuttle 27 and the dumping or ejection of filled and closed shells from the remaining shuttle or shell holder 27. Suitable means may be provided to catch 30 the closed and completed shells dumped from the lowermost shuttle 27, but I prefer to employ a rotatable table 28 which may be conveniently mounted on one of the uprights 1 for the reception of succeeding batches of filled and closed shells and the even distribution over its surface of the shells so that they may be conveniently and regularly removed by hand.

I prefer to employ shuttles, embodying 40 my own invention at 27, but I do not restrict my invention in its broadest aspect to any particular type of shuttle 27. Preferably, the shuttles 27 are controlled in their opening and closing movements by motive fluid pressure and in order that this be accomplished automatically so that the shell carrier 26 is rotated step by step, I provide the mechanism shown in Fig. 5.

Carried by the shaft 29 to which the shell 50 carrier 26 is connected, are the actuating wheel 30 and the locking wheel 31, the former being provided with teeth 32 and the latter with notches 33. The periphery of wheel 31 is formed so that one side of each 55 notch 33 is lower than the other side thereof, the higher side being that against which the locking device will engage. This insures the entry of the locking device into the notches 33 and accuracy in stopping and 60 holding the shell carrier 26 at the points at which it should be arrested. The locking device is shown at 34 as slidably mounted and guided in the supplemental frame 1^a, the top of the locking device being adapted to ride 65 on the periphery of the locking wheel 31. A

spring 35 tends to snap the locking device into the notches 33. The locking device is provided with a piston 36 operating in the cylinder 37.

The actuating device has a pawl 38 and a 70 piston rod 39 jointed at 40, a spring 41 being adapted to cause the pawl 38 to press against the periphery of the actuating wheel 30. The spring 41 also permits the pawl 38 to yield as will be necessary due to the turning of the actuating wheel 30 when it is causing it to partly revolve. The piston rod 39 is suitably guided in frame 1^a and provided with a piston 42 operating in cylinder 43. A pipe 44 connects the lower end of the cylinder 37 with the upper end part of the cylinder 43. The respective cylinders 37 and 43 are adapted to be supplied with motive fluid pressure such as air through pipes 45 which convey said pressure to the upper 85 ends of the cylinders above the respective pistons 36 and 42. The supply of air through the pipes 45 is controlled in a manner hereinafter set forth, but if it be assumed that pressure has been admitted to 90 the pipes 45, it will be evident that the pistons 36 and 42 will be forced downward in their cylinders, causing the locking device 34 to be retracted from notch 33 and the actuating device 38, 39, to engage a tooth 95 32 and turn the wheels 30 and 31, as also the shaft 29, and hence the shell carrier 26, which movement will continue until checked by the checking device 46 which has a head 47 adapted to be made to enter notch 33 by 100 the action of a spring 48. The checking device 46 is seated in a cushioning device such as the spring dash-pot 49, whereby the turning movement imparted to the wheels 30, 31, is prevented from being too abrupt. The 105 checking action in question takes place just prior to a notch 33 coming in alignment with the locking device 34, but before such locking takes place, a member 50 on the checking device 46 strikes a bracket 51 on frame 1^a which throws the tooth 47 out of the notch 33 with which it has been engaged. Immediately the piston 42 passes the point where pipe 44 enters cylinder 43, the air pressure entering cylinder 43 at the top 115 through pipe 45 is immediately by-passed through pipe 44 into cylinder 37 and thereupon ensues a tendency toward balancing of the air pressure on opposite sides of the piston 36 so that the spring 35 immediately 120 becomes effective to snap the latch 34 into the notch 33 and the wheels 30 and 31 and the carrier 26 are thus arrested and locked.

The controlling mechanism hereinafter set forth supplies and cuts off the pressure 125 to the pipes 45 at all such periods as will cause a step by step rotation of the carrier 26 and its locking so that the respective shell holders or shuttles 27 may receive shells, the shells be filled, then closed, and 130

then dumped or ejected onto the table 28, in the order given.

I do not limit myself to the use of the particular shell holder or shuttle set forth herein, but prefer it. This shell holder or shuttle forms the subject-matter of a separate application for patent filed April 24, 1912, Serial No. 692932.

Referring to Figs. 14 to 21, so much of the shell holder is set forth as will give a clear understanding of its construction and operation in connection with the present invention. The shell holder may be single or double, the latter construction being shown and preferably employed as it has double the capacity.

The base 52 is connected to the carrier 26. Rising from and secured to the base is a stationary center leaf 53 having grooves 54 on its opposite sides. Projecting in opposite directions from the center leaf are guide rods 55. The end leaves are shown at 56 and the intermediate leaves at 57. The intermediate leaves have grooves 58 on their opposite sides corresponding to the end leaf grooves 59. The grooves are substantially semi-circular in cross-sectional outline and are adapted to form the respective shell holding pockets which correspond in arrangement and number to the nipples 6. The leaves 56, 57, have holes 60 which loosely receive the rods 55. The leaves have countersunk portions 61 in which are received and held springs 62 whose projecting parts bear against the mating leaves. Four springs are interposed between each pair of leaves, two at each end, whereby the leaves are adapted to open quickly and easily. To close the leaves, there are provided at each end of the center leaf 53 cylinders 64 which may be suitably attached thereto in any preferred manner. Within the cylinders are pistons 65, 66, having piston rods 67, 68, connected to the respective end leaves 56. The cylinders have a port 69 having branches whose ends open thereinto between the respective pistons 65, 66, and the cylinder heads, so that on the admission of air, the pistons are forced toward each other against the action of the springs 61, 62, thus closing the leaves together and holding the shells in the pockets between the leaves. When the air pressure is released, the springs 61, 62, immediately open the leaves, permitting empty shells to be inserted in the pockets or any shells held thereby to be released. The cylinders 64 receive their air from pipes 70 carried by the carrier 26 and communicating with the hollow part of shaft 29 which is supplied with air pressure by a pipe 71 which is at all times subject to the air pressure. The pipes 70 are provided with valves 72 which are adapted to be turned to admit or cut off the air supply to pipes 70 by a cam 73, the arrangement

being such that there is no supply of air to the cylinders 64 of the shuttle 27 which is opposite the shell placing mechanism nor to the shuttle which is in lowermost position ready to discharge the loaded shells onto the table 28, the other shuttles 27 which are located, respectively, in position for loading of the shells and for closing of the shells, having their valves 72 open to admit the air pressure to the cylinders 64 so that the shells are suitably held. The valve 72 of the shuttle is opened shortly after the given shuttle passes from shell receiving position toward shell loading position so that the shells are held in position to receive the nipples 6. 80

In the use of shell holders or shuttles there is sometimes a tendency on the part of a few of the loaded shells to stick to the leaves of the shuttle so that discharge by gravity is prevented. To obviate this difficulty, I provide movable false bottoms 74 on which the shells are adapted to rest. The bottom or base 52 is provided with recesses 75 to permit the false bottoms to lie flush with the upper faces of said bottom 52 and the lower edges of the leaves 57 are recessed at 76 to permit the false bottoms to have a slight play outward. When the shuttle is inverted, the weight of the false bottom 74 causes the shells to be positively ejected and prevents any of them from adhering to the leaves. To amplify the ejective action of the false bottom 74, I provide weights 77 adapted to coöperate therewith. These weights may be of any preferred material. 100 In the present machine, I arrange the weights inside the carrier 26 and provide them with pins 78 slidable in openings in the carrier and adapted to abut against pins 79 on the false bottoms 74. To equalize the ejective action of the weights on the false bottoms, a plurality of pins 78 and 79 are provided to coöperate with each false bottom. In the shell carrier system of the present machine, two of the weights 77 may be of open rectangular form and the remaining two of I-shape and extending therethrough and arranged crosswise of those of open rectangular form. With the arrangement set forth, the movable bottoms 74 of the shell holding shuttle which is uppermost and whose shells are being loaded are in depressed position and the false bottoms 74 of the opposite shell holding shuttle which is in discharging position over the table 28, receives the full ejective effect of the weights 77. 110

Located at the side of the table 28 and in position to assemble and direct the empty paper shells into the shell holders or shuttles 27 when they are opposite thereto, is the shell placing or assembling mechanism which is supported on a frame 1^b. 125

Surmounting the frame 1^b is an elongated guide frame 80 having tracks 81 extending 130

lengthwise thereof and parallel to each other. Mounted to travel on these tracks by sliding thereon or by the use of rollers, is a carriage 82 which is provided with shelves 83 corresponding in number to the number of rows of shell-holding pockets or receptacles in the shell holding shuttles 27 and adapted to support rows of shells which are to be inserted in the pockets of the respective rows of shuttles. Leading to these shelves 83 are inclined guides 84 corresponding in number thereto whose extremities 85 are more nearly parallel to the shelves 83 than are the guides 84. The parts 85 being nearly horizontal, do not tend to dent or crush the shells when coming in contact with them and they direct them to the guides 84, which, due to their greater inclination, more rapidly direct the paper shells to the shelves 83, as will presently appear. The shelves 83, inclined guides 84 and parts 85 are arranged in two parallel sets above the tracks 81, there being a space between the said sets for the accommodation of the vertically extending agitators and division members 86 which are arranged in spaced relation, in position corresponding to the rows of shell holding pockets or receptacles of the shell holding shuttles 27. The carriage 82 carries serpentine or other suitable cam tracks 87 on which the lower ends of the division plates 86 rest, legs 88 having rollers 89 being preferably provided for this purpose. The shell holding hopper 90 which contains the shells 91 is arranged so that the outlet 92 receives the upper ends of the division plates 86. The parts being in this position, the shells 91 naturally fall in superposed position between the division plates 86, but to prevent any crowding or inequality of positioning, the division plates 86 are arranged to vibrate up and down as the carriage 82 moves to and fro.

Slidably mounted on the frame 1^b so as to move at right angles to the carriage 82 is another carriage 93 which carries the pusher pins 94 corresponding in number to the shell-holding receptacles or pockets in the shuttles 27 and to the position and number of the nipples 6. The free ends of these pusher pins 94 are pointed at 95, there being provided a shoulder 96 which is of a proper size to engage the edge of the shell at its mouth after the pointed end 95 has entered the shell. The pointed ends 95 insure the engagement of the pusher pins with the shells without likelihood of damaging the latter, the pointed construction permitting the end of the pin to easily enter the mouth of the shell and the shoulder 96 effecting the pushing of the shells into the shuttle 27 from between the division plates 86 and off of the shelves 83. A cylinder 97 carried by frame 1^b and a piston 98 therein which has a piston rod 99 connected to carriage 82, affords

means for causing the carriage 82 to play to and fro. A cylinder 100 secured to frame 1^b has a piston 101 and piston rod 102 connected to the frame 93, whereby the frame 93 and the pusher pins 94 are made to move to and fro. The compressed air is admitted to cylinder 97 through pipe 103, in turn automatically controlled, as will presently appear. Compressed air is admitted to cylinder 100 by pipe 104 and automatically controlled in a manner hereinafter set forth. At the far end of the cylinder 97 from pipe 103 two by-pass pipes 105 and 106 connect that cylinder with an end of cylinder 100 opposite the end connected to pipe 104. Assuming that the shell holding shuttle 27 is in position for the placing therein of the shells 91, and that they have dropped into the spaces between the division plates 86, when pressure is supplied through pipe 103 to cylinder 97, it forces the piston 98 to the far end of the cylinder. This movement is not abrupt, due to the provision of an oil check similar to the oil checks 12, 13, 14. The carriage 82 by its travel, causes the receiving parts 85 to enter under the shells between the division plates 86, without injury to the shells, the shells being let down the inclined guides 84 until they eventually rest upon the shelves 83 in a position lower than that in which they formerly reposed. When the shelves 83 are arranged crosswise of the division plates 86, the shells are assembled or classified in a manner corresponding to the shell holding pockets or receptacles in the shuttles 27 and they are exactly in line with those pockets and ready to be pushed into them. The disposition of the shelves 83 crosswise of the division plates 86 occurs when the piston 98 has passed beyond the point where the pipe 105 enters cylinder 97, and as soon as this occurs the pressure from pipe 103 passes via pipe 105 into the cylinder 100, immediately forcing the piston 101 to the end of the cylinder carrying with it the frame 93 and the pusher pins 94 whose points 95 first enter the shells and whose shoulders then push the shells into the pockets or receptacles in the shuttle 27. An oil check 151 prevents the movements of the pusher pins from being too abrupt.

As will presently appear, the controlling mechanism later on opens the pipe 103 to exhaust and pressure is admitted to pipe 104 to force the piston 100 back to its normal position, whereupon the pressure entering through pipe 104 enters pipe 106 and forces piston 98 back to its normal position. There is then a balanced condition of pressure on opposite sides of piston 101, which continues until the pipe 104 is opened to exhaust.

The mechanisms now to be described may be mounted in any preferred position but, preferably, the trip mechanism and the

pilot valve are disposed on the frame 1 or yoke 2 in position for convenient tripping and manual control.

At 107 is disclosed a four-way pilot valve which controls the operation of the entire machine. Air pressure from any suitable source is supplied to the valve casing by pipe 108; 109 is an exhaust branch for the valve. At 110 is shown a controlling cylinder, one end of which has a pipe connection 111 with the four-way valve 107 and the opposite end a pipe connection 112 with said valve 107. A lever 113 is carried by the valve and adapted for operating it, said lever being pulled in one direction by a spring 114 and adapted to be pulled in the opposite direction by hand or through the intervention of a cord or chain 115 if disposed out of convenient reach of the operator. The spring 114 maintains the valve 107 in such position that air will exhaust from cylinder 110 through pipes 112 and 109 and will be admitted from supply pipe 108 to pipe 111. At 116 is a four-way master valve which is operated by a piston 117 in cylinder 110 and a piston rod 118 connected to said valve. A suitable dash-pot 119 is connected to piston rod 118. When the parts are in the position set forth, the supply of air through the pipe 111 maintains piston 117 in such position that the four-way master valve 116 is so positioned that all the mechanisms are retracted so as to be ready to perform their respective functions. At 120 is a latch which has an offset end 121 adapted to lock the end 122 of lever 113 when said lever is raised by pulling on the cord 115 against the action of spring 114. The latch 120 is maintained in position after locking lever 113 by a spring 123. The latch 120 may be moved in opposition to spring 123 to release lever 113 if engaged therewith by a cord 124. The carriage 3 carries a trip 125 which is adapted to engage the latch 120 on the return of the carriage to its raised position after the shells in the shuttle have been filled, and the lever 113 being engaged with the part 121 during the previous operation of the machine, is thereupon released so that the lever 113 resumes its normal position, placing the different cylinders in communication with their exhausts.

Referring to diagrammatic Fig. 4, the arrangement of the cylinders, their piping, valves and controlling mechanisms are there-in disclosed. The upper ends of cylinders 7 and 16 are connected to master valve 116 by pipes 126, the valve placing these pipes and pipe 131 in communication with the exhaust 128 of the master valve when the parts are in normal position. The lower ends of cylinders 7 and 16 have pipe connections 129 and 130, both communicating with the pipe 131 which leads to the master valve 116. At 65 a suitable point in the pipe 126 is a pressure

70 checking valve 132 of any preferred type which momentarily cuts down the pressure entering pipes 126 from the feed pipe 108 so that a too sudden application of pressure to the pistons 8 and 17 will be prevented as it would result in too abrupt descent of the carriage 3 and too abrupt forcing of the explosive into the shells. In the pipe 131 there is introduced a check valve 133 which permits a slow exhaust from the cylinders 7 and 16 below the pistons 8 and 17 thereof when the air is exhausting, or, a rapid supply of pressure when it is introduced via pipe 129 into the lower end of said cylinder 16 to raise the piston therein, thus 80 providing for a quick lifting action of the carriage 3. In the pipe 130 there is provided a pressure reducing valve 134 which permits a quick introduction of pressure through pipe 130 below the piston 8 so that 85 it may be quickly returned upwardly after the shells have been loaded. A valve 135 in a by-pass pipe 136 permits only an exhaust of the pressure from below the piston 8 when the latter is descending to force the 90 explosive into the shells.

The admission of pressure to cylinder 97 is via pipe 137 and is checked by the same valve 132 which controls the supply above pistons 8 and 17; the pressure exhausts from cylinder 97 through pipes 137, 126, valves 132 and 116 and exhaust pipe 128. Pipe 104 which connects with pipe 131 receives pressure through valve 133 and supplies it to cylinder 100, or, on the other hand, the pressure 100 slowly exhausts through valve 133 when the carriage 82 of the shell assembler has been moved by its piston 98 to such position that pressure will be admitted through pipe 105 to cylinder 100.

105 Located diametrically opposite the shell assembling mechanism is the shell closing mechanism which is carried by a frame 1^c having vertical and horizontal parts, the vertical members of which are provided with a yoke 139. Slidable on the horizontal part of the frame 1^c is a shell closing head 140 embodying a pressure plate 141 provided with concavities 142 adapted to receive the free ends of the loaded shells and held in separated position in relation to the other member 143 of the head 140 by springs 144. Pins 145 carried by the member 143 pass through openings in the plate 141 which communicate with the concavities 142, the pins being adapted to push in the center of the shell end after it has been closed or crimped by the concavities 142. This shell closing mechanism is substantially the same as set forth in my Patent No. 995046, dated June 13, 1911. The manner of operating the shell closing device is, however, different from what I have heretofore used or what has been known to the art. I wish it understood that the shell closing devices 130

140-145 may be changed and other shell closing means employed. The operating means for the shell closer embodies a cylinder 146 carried by the yoke 139, a piston 147 therein and a piston rod 148 connected to the member 143. Oil checks 149 similar to the oil checks 12, 13, 14, heretofore described, are employed to check the to and fro movement of the shell closer. Leading 5 to opposite ends of the cylinder 146 and on opposite sides of the piston 147 therein are pipes 150 and 151, the former being connected to the pipe 137 and the latter to the pipe 130. Consequently the pressure checking valve 132 prevents too sudden access of 10 pressure to the rear of piston 147 when the shell closer goes forward toward the shell carrier 26 to close the loaded shells and the pressure checking valve 133 also prevents 15 too sudden exhaust of pressure from the opposite face of piston 147 through pipes 151, 136 and 131. Therefore, it will be observed, that the movements of the piston 147 20 are controlled by the same valves and at the same time as also in the same manner as are 25 the movements of the pistons 8 and 17.

Similarly, the access of pressure to the cylinder 97 and the exhaust therefrom, as also the admission of pressure to cylinder 30 100 and exhaust therefrom, are substantially simultaneously controlled. The only mechanism which is not simultaneously controlled with the shell placing, shell feeding, and shell closing mechanisms is the 35 mechanism for turning the carrier 26 step by step. I provide a three-way hand-operated valve 152 at a suitable point in the pipe 153 which leads to the pipes 45 that control the cylinders 37 and 43. When this valve 40 is turned one way, pressure is admitted through pipes 108 and 153 to the pipes 45 and when it is turned to another position, the pressure in the cylinders 37 and 43 may 45 exhaust at 154.

45 The pipe 126 is provided with a three-way valve 155 which controls said pipe and also an exhaust pipe 156 having a relief valve 157. The valve 157 may be of any preferred type which is adapted to be set to open at 50 any predetermined pressure. The valve 155 is automatically operated by a rod 158 having stops 159 and 160 and it is arranged so that a bracket 161 on the carriage 3 is adapted to engage the stops 159 and 160 at different points. Pressure having been admitted into the pipe 126, the carriage 3 is forced 55 downwardly by piston 17 to position the nipples 6 in the shells. At the proper point of movement, the bracket 161 strikes the stop 160, thereupon turning the valve 155 to release the pressure from above the piston 17 into the pipe 156. The valve 157, according to the pressure at which it has been set to let off, determines the density of the explosive gelatin or other material forced into 60 the shells because the carriage 3 will remain down until it is forced upwardly by the reactive pressure of the explosive in the shells, as the shells are filled by the plunger 10. Eventually the lift of the carriage caused by 70 the filling of the shells causes the trip 125 to strike the latch 120 and press it aside, thereby releasing the lever 113 whose spring 114 immediately snaps it to its normal position, whereupon the air pressure from pipe 108 75 passes through the pilot valve 107 into pipe 111, resulting in the master valve 116 being reversed. The reversal of the master valve causes the air to pass into pipes 129 and 104 and also into pipes 130 and 151. The 80 carriage is thereupon raised to its full height by the admission of air under the piston 17 and the bracket 161 strikes the stop 159, thereby returning the three-way valve 155 to its normal position where it is adapted to 85 permit pressure, when entering pipe 126, to pass to the cylinder 16 on the next operation of the machine. The access of pressure through pipe 130, forces the piston 8 upwardly and the piston 147 backwardly. 90 These movements are substantially quick return movements. The access of pressure into pipe 104 simultaneously with the quick return of the other pistons, forces the piston 101 back to normal position and immediately this occurs, the pressure is admitted via pipe 106 so that it acts on piston 98 and forces the latter back to normal position. The parts are thus all restored to normal position. The rotary carrier 26 can now 100 be turned by moving valve 152 to admit pressure to the cylinders 37 and 43 which thereupon operate their pistons in a manner heretofore set forth, causing the carrier 26 to turn a quarter revolution, thus bringing the loaded shells into line with the shell closing mechanism, the shells which have been placed in a shuttle into line with the loading mechanism, the positioning of a 105 shuttle carrying any previously loaded and closed shells to discharging position over the table 28 and another empty shuttle into line with the shell placing mechanism. As previously set forth, the valves 72 of the respective shuttles and the cam 73 are so arranged that air pressure is admitted to the 110 shuttles which are in loading and closing position and is released from the shuttles which are in discharging and placing positions.

115 On pulling the cord 115 or moving the lever 113 to latch it at 121, operations such as previously set forth ensue. The master valve 116 is reversed, the air is admitted into pipes 126 at checked pressure, whereby the carriage is forced downward by piston 17 120 to position the nipples in the empty shells. The piston 8 also forces the plunger 10 into the hopper 4, forcing out the explosive into the shells. With respect to the loading mechanism, the filling of the shells takes 130

place as previously described. Simultaneous with the filling of the shells, the pressure entering pipes 137 and 103 passes into cylinder 97 of the shell placing mechanism, thereupon moving the carriage 82 to its extreme limit, but as soon as this occurs, the pipe 105 is uncovered and the pressure passes into cylinder 100, whereupon the piston 101 of the pusher pin mechanism is moved to its extreme limit to place the shells in the empty shuttle, but as soon as this occurs, the pipe 106 is uncovered, whereupon the pressure passes back into cylinder 97 and a balanced condition of pressure exists on both sides of piston 98. Simultaneous with the loading and shell placing operations, the pressure passes through pipes 126, 137 and 150 and operates the piston 147 to effect the closing of the shells. The parts being in the positions indicated, the rising of the carriage due to the reactive pressure of the explosive gelatin on the nipples, the hopper, and hence the carriage causes the carriage to retreat, the stop 159 being struck and the residuary pressure above piston 17 is then let off through pipe 156; also, the trip 125 engages the latch 120 and releases the lever 113, whereupon the return of the parts to normal position takes place, as previously set forth.

As shown by dotted lines at the left of Fig. 4, the valve 152 may be automatically opened and closed by providing it with a depending rod 168 having adjustable stops 169, 170, adapted to be engaged by a bracket 171 on the cylinder 7. At the proper point of upward movement of the cylinder 7, bracket 171 strikes stop 169, thereby turning valve 152 to allow air pressure to pass into pipe 153. When the carriage 3 descends for the loading of the next shuttle, the bracket 171 strikes stop 170, turning valve 152 and allowing air to exhaust at 154, thereby permitting the shell carrier actuating device to return to normal position. With this mechanism the shell holding shuttles may be automatically moved and operated.

Having thus described my invention, what I claim as new and desire to secure by Letters Patent, is:

1. In a shell loading machine, the combination with a plurality of movably mounted shell holders each having means for holding a plurality of shells in grouped arrangement, of shell assembling means adapted automatically to segregate and group a plurality of shells in the arrangement and relation they are adapted to assume in the shell holder and then automatically to place the entire group of said shells in said movable shell holder when the latter is in receiving position with relation to the shell assembling means, and means for moving the shell holders to place an unfilled holder in po-

sition for filling and to place a previously filled shell holder in position for a subsequent operation on the shells therein.

2. In a shell closing machine, the combination with a shell closer, of means for moving said shell closer bodily to and from embodying a piston and cylinder, means for supplying fluid pressure alternately to opposite sides of the same piston to cause either the advance or the retreat of the shell closing means, and pressure checking means controlling the admission of pressure to, and exhaust of pressure from, the piston when it is acting to close the shells.

3. In a shell loading machine, the combination with a rotary shell carrier adapted to turn step by step, of independent means for automatically turning, then checking and automatically releasing and finally arresting said carrier during its step by step movements.

4. In a shell loading machine, the combination with a rotary shell carrier adapted to turn step by step, of fluid pressure operated automatically acting means adapted both to turn and to arrest the carrier, said turning means operatively engaging said shell carrier to turn the carrier before the release of said arresting means.

5. In a shell loading machine, the combination with a rotary shell carrier adapted to turn step by step, of independent fluid pressure operated means arranged and adapted for intercontrol, one of which is adapted to turn the carrier and the other to lock it and connections between said means whereby they are operated in succession.

6. In a shell loading machine, the combination with a rotary shell carrier adapted to turn step by step, of an operating cylinder and piston for turning the carrier, a separate cylinder and piston for locking the carrier, means for supplying fluid pressure to one side of the pistons aforesaid, and a by-pass pipe connecting the cylinders on the other side of the pistons thereof, whereby the respective cylinders and pistons are intercontrolled.

7. In a shell loading machine, the combination with a rotary shell carrier adapted to turn step by step, of an operating cylinder and a piston for turning the carrier, a separate cylinder and piston for locking the carrier, means for supplying fluid pressure to one side of the pistons aforesaid, a by-pass pipe connecting the cylinders on the other side of the pistons thereof, whereby the respective cylinders and pistons are intercontrolled, a spring adapted to position the carrier-turning device for co-operation with the carrier, and a spring adapted to position the carrier-locking device for locking the carrier.

8. In a shell loading machine, the combination with a rotary shell carrier adapted for an intermittent movement, of means for turning said carrier, a checking device embodying a shiftable cushioned member, and means for automatically releasing the checking device after it has checked the carrier, whereby the carrier is automatically released after being checked. 65
- 10 9. In a shell loading machine, the combination with a rotary shell carrier, of a locking wheel having notches or recesses whose shoulders are higher on one side than on the other, a releasable checking device adapted to ride on said wheel and to engage the recesses and shoulders thereof, a locking device adapted to ride on the wheel and to engage the recesses and shoulders thereof, and means for automatically releasing the checking device prior to the engagement of the locking device with the wheel. 70
- 15 10. In a shell loading machine, the combination with a shell carrier, of a locking wheel therefor, an actuating wheel therefor, the locking wheel having notches and shoulders and the actuating wheel being provided with teeth, a cylinder, a piston operating therein, a latch connected to the piston adapted to engage the notches and shoulders 75
- 20 30 of the locking wheel, a cylinder, a piston operating therein, a pawl connected to the piston and adapted to engage and turn the actuating wheel, springs adapted, respectively, to position the latch for engagement with the notches and the pawl for engagement with the actuating wheel, means for admitting fluid pressure to the cylinders on one side of the pistons thereof, a by-pass pipe connecting the cylinders on opposite 80
- 25 40 sides of the pistons thereof, a spring cushioned device arranged to ride on the locking wheel and to engage the notches and shoulders thereof prior to the adaptation of the parts for engagement of the latch with a notch and shoulder, and means adapted 85
- 30 45 automatically to kick off or release the checking device after it has checked the rotation of the carrier and prior to the engagement of the latch with a notch and shoulder. 90
- 35 50 11. In a shell loading machine, the combination with a fluid pressure operated feeder, of a fluid pressure operated shell assembler and placer, a fluid operated shell closer, a shell holder adapted for the placing therein 95
- 40 55 of the shells by the assembler, the loading of the shells by the feeder, and the closing of the shells by the closer, pipe connections to the feeder, shell assembler, and closer, respectively, a valve common to all of said 100
- 45 60 mechanisms, and means for regulating the fluid pressure supplied to the feeder, assembler, and closer to prevent too abrupt movements thereof when they start to perform their operations, said means and pipe con- 105
- 50 nections permitting the feeder, the assembler, and the closer to return quickly to normal position under the action of the fluid pressure supplied thereto for that purpose. 110
- 55 65 12. In a shell loading machine, the combination with shell-placing means, of a movable shell holder adapted to receive the empty shells from said placing means, loading means adapted to load fully at one operation of said means the empty shells previously placed in the shell holder, and controlling means common to the shell placing means and the loading means aforesaid adapted to control substantially simultaneously said shell placing means and said shell loading means. 115
- 60 65 13. In a shell loading machine, the combination with fluid pressure operated shell placing means, of a movable shell holder adapted to receive the empty shells from said placing means, fluid pressure operated loading means adapted to load the empty shells previously placed in the shell holder, a single controlling means, and connections between said controlling means and the fluid pressure operated shell placing means and the fluid pressure operated loading means aforesaid adapted to control substantially simultaneously said shell placing and said loading means. 120
- 65 70 14. In a shell loading machine, the combination with fluid pressure operated shell placing means, of a movable shell holder adapted to receive the empty shells from said placing means, fluid pressure operated loading means adapted to load fully at one operation of said means the empty shells previously placed in the shell holder, and controlling means common to the fluid pressure operated shell placing means and the fluid pressure operated loading means aforesaid adapted to control substantially simultaneously said shell placing and said loading means. 125
- 70 75 15. In a shell loading machine, the combination with a movable shell holder of means to load the shells at one operation of said means, and shell crimping means adapted successively to close the loaded shells, and controlling means common to the shell loading means and shell crimping means aforesaid, adapted to control substantially simultaneously said loading means and said crimping means. 130
- 75 80 16. In a shell loading machine, the combination with a movable shell holder, of fluid pressure operated shell loading means, fluid pressure operated shell crimping means, said loading means and said crimping means being adapted successively to cooperate with empty shells previously placed in the shell holder, and controlling means common to the fluid pressure operated shell loading means and fluid pressure operated 135

shell crimping means aforesaid, adapted to control substantially simultaneously said loading and said crimping means.

17. In a shell loading machine, the combination with a movable shell holder, of fluid pressure operated shell loading means adapted to load at one operation of said means shells in said holder, fluid pressure operated shell crimping means, said loading means and said crimping means being adapted successively to cooperate with empty shells previously placed in the shell holder, and controlling means common to the fluid pressure operated shell loading means and fluid pressure operated shell crimping means aforesaid, adapted to control substantially simultaneously said loading and said crimping means.

18. In a shell loading machine, the combination with shell placing means, of a movable shell holder adapted to receive empty shells from said shell placing means, loading means adapted to load fully at one operation of said means the empty shells previously placed in the shell holder, closing means adapted to close the loaded shells, and controlling means common to the shell placing means, shell loading means, and shell closing means, adapted to control substantially simultaneously said placing means, said loading means, and said closing means.

19. In a shell loading machine, the combination with fluid pressure operated shell placing means, of a movable shell holder adapted to receive the empty shells from said placing means, fluid pressure operated loading means adapted to load the empty shells previously placed in the shell holder, fluid pressure operated closing means adapted to close the loaded shells, pipes leading to said placing means, said loading means, and said closing means, and a valve adapted simultaneously to control the pressure supplied through said pipes to said placing means, said loading means, and said closing means.

20. In a shell loading machine, the combination with fluid pressure operated shell placing means, of a movable shell holder adapted to receive the empty shells from said placing means, fluid pressure operated loading means adapted to load at one operation of said means the empty shells previously placed in the shell holder, fluid pressure operated closing means adapted to close the loaded shells, pipes leading to said placing means, said loading means, and said closing means, and a valve adapted simultaneously to control the pressure supplied through said pipes to said placing means, said loading means, and said closing means.

21. In a shell loading machine, the combination of a vertically immovable shell carrier adapted to rotate about a horizontal

axis and having shell holding pockets, and coöperating means adjacent said shell carrier adapted to assemble shells at the proper height and in proper position ready for placing in said pockets.

22. In a shell loading machine, the combination of a vertically immovable shell carrier adapted to rotate about a horizontal axis and having shell holding pockets, and coöperating means adjacent said shell carrier adapted to place shells in said pockets.

23. In a shell loading machine, the combination of a vertically immovable shell carrier adapted to rotate about a horizontal axis and having shell receiving pockets, and coöperating means adjacent said shell carrier adapted to crimp loaded shells in said pockets.

24. In a shell loading machine, the combination of a vertically immovable shell carrier adapted to rotate about a horizontal axis, coöperating with means to assemble shells ready for placing therein, and with means to place the assembled shells therein.

25. In a shell loading machine, the combination of a vertically immovable shell carrier adapted to rotate about a horizontal axis, coöperating with means adjacent said shell carrier and at the proper height with respect thereto to assemble shells ready for placing therein, and with means to load shells placed therein.

26. In a shell loading machine, the combination of a vertically immovable shell carrier adapted to rotate about a horizontal axis, coöperating with means adjacent said shell carrier and at the proper height with respect thereto to assemble shells ready for placing therein, and with means to close loaded shells therein.

27. In a shell loading machine, the combination of a vertically immovable shell carrier adapted to rotate about a horizontal axis, coöperating with means adjacent said shell carrier and at the proper height with respect thereto to assemble shells ready for placing therein, and with means to discharge completed shells therefrom.

28. In a shell loading machine, the combination of a vertically immovable shell carrier adapted to rotate about a horizontal axis, coöperating with means to place shells therein, and with means to load shells placed therein, said operations taking place practically simultaneously at stations arranged around said carrier.

29. In a shell loading machine, the combination of a vertically immovable shell carrier adapted to rotate about a horizontal axis, coöperating with means to place shells therein, and with means to close loaded shells therein, said operations taking place practically simultaneously at stations arranged around said carrier.

30. In a shell loading machine, the combi-

nation of a vertically immovable shell carrier adapted to rotate about a horizontal axis, coöperating with means to place shells therein, and with means to discharge completed shells therefrom, said operations taking place practically simultaneously at stations arranged around said carrier.

31. In a shell loading machine, the combination of a vertically immovable shell carrier adapted to rotate about a horizontal axis, coöperating with means to load shells placed therein, and with means to crimp loaded shells therein, said operations taking place practically simultaneously at stations arranged around said carrier.

32. In a shell loading machine, the combination of a vertically immovable shell carrier adapted to rotate about a horizontal axis, coöperating with means to crimp loaded shells therein, and with means to discharge completed shells therefrom, said operations taking place practically simultaneously at stations arranged around said carrier.

33. In a shell loading machine, the combination of a vertically immovable shell carrier adapted to rotate about a horizontal axis, coöperating with means to assemble shells ready for placing therein, with means to place the assembled shells therein, and with means to load shells placed therein.

34. In a shell loading machine, the combination of a vertically immovable shell carrier adapted to rotate about a horizontal axis, coöperating with means to assemble shells ready for placing therein, with means to place shells therein, and with means to close loaded shells therein.

35. In a shell loading machine, the combination of a vertically immovable shell carrier adapted to rotate about a horizontal axis, coöperating with means to assemble shells ready for placing therein, with means to place shells therein, and with means to discharge completed shells therefrom.

36. In a shell loading machine, the combination of a vertically immovable shell carrier adapted to rotate about a horizontal axis, coöperating with means adjacent said shell carrier and at the proper height with respect thereto to assemble shells ready for placing therein, with means to load shells placed therein, and with means to close loaded shells therein.

37. In a shell loading machine, the combination of a vertically immovable shell carrier adapted to rotate about a horizontal axis, coöperating with means adjacent said shell carrier and at the proper height with respect thereto to assemble shells ready for placing therein, with means to load shells placed therein, and with means to discharge completed shells therefrom.

38. In a shell loading machine, the combination of a vertically immovable shell car-

rier adapted to rotate about a horizontal axis, coöperating with means adjacent said shell carrier and at the proper height with respect thereto to assemble shells ready for placing therein, with means to close loaded shells therein, and with means to discharge completed shells therefrom.

39. In a shell loading machine, the combination of a vertically immovable shell carrier adapted to rotate about a horizontal axis, coöperating with means to place shells therein, with means to load shells placed therein, and with means to close loaded shells therein, said operations taking place practically simultaneously at stations arranged around said carrier.

40. In a shell loading machine, the combination of a vertically immovable shell carrier adapted to rotate about a horizontal axis, coöperating with means to place shells therein, with means to load shells placed therein, and with means to discharge completed shells therefrom, said operations taking place practically simultaneously at stations arranged around said carrier.

41. In a shell loading machine, the combination of a vertically immovable shell carrier adapted to rotate about a horizontal axis, coöperating with means to place shells therein, with means to close loaded shells therein, and with means to discharge completed shells therefrom, said operations taking place practically simultaneously at stations arranged around said carrier.

42. In a shell loading machine, the combination of a vertically immovable shell carrier adapted to rotate about a horizontal axis, coöperating with means to load shells placed therein, with means to crimp loaded shells therein, and with means to discharge completed shells therefrom, said operations taking place practically simultaneously at stations arranged around said carrier.

43. In a shell loading machine, the combination of a vertically immovable shell carrier adapted to rotate about a horizontal axis, coöperating with means to assemble shells ready for placing therein, with means to place shells therein, with means to load shells placed therein, and with means to crimp loaded shells therein.

44. In a shell loading machine, the combination of a vertically immovable shell carrier adapted to rotate about a horizontal axis, coöperating with means to assemble shells ready for placing therein, with means to place shells therein, with means to load shells placed therein, and with means to discharge completed shells therefrom.

45. In a shell loading machine, the combination of a vertically immovable shell carrier adapted to rotate about a horizontal axis, coöperating with means to assemble shells ready for placing therein, with means to place shells therein, with means to close

loaded shells therein, and with means to discharge completed shells therefrom.

46. In a shell loading machine, the combination of a vertically immovable shell carrier adapted to rotate about a horizontal axis, coöperating with means adjacent said shell carrier and at the proper height with respect thereto to assemble shells ready for placing therein, with means to load shells placed therein, with means to close loaded shells therein, and with means to discharge completed shells therefrom.

47. In a shell loading machine, the combination of a vertically immovable shell carrier adapted to rotate about a horizontal axis, coöperating with means to place shells therein, with means to load shells placed therein, with means to close loaded shells therein, and with means to discharge completed shells therefrom; said operations taking place practically simultaneously at stations arranged around said carrier.

48. In a shell loading machine, the combination of a vertically immovable shell carrier adapted to rotate about a horizontal axis, coöperating with means to assemble shells ready for placing therein, with means to place shells therein, with means to load shells placed therein, with means to close loaded shells therein, and with means to discharge completed shells therefrom.

49. In a shell loading machine, a shell carrier, and coöperating but separate means automatically, substantially simultaneously, and at one operation, to assemble shells ready for placing in said shell carrier and to place shells therein.

50. In a shell loading machine, a shell carrier, and coöperating but separate means automatically, substantially simultaneously, and at one operation, to assemble shells ready for placing in said shell carrier and to load shells placed therein.

51. In a shell loading machine, a shell carrier, and coöperating but separate means automatically, substantially simultaneously, and at one operation, to assemble shells ready for placing in said shell carrier and to close loaded shells therein.

52. In a shell loading machine, a shell carrier, and coöperating but separate means automatically, substantially simultaneously, and at one operation, to assemble shells ready for placing in said shell carrier and to discharge completed shells therefrom.

53. In a shell loading machine, a shell carrier, and coöperating but separate means automatically, substantially simultaneously, and at one operation, to assemble shells ready for placing in said shell carrier, to place shells therein, and to load shells placed therein.

54. In a shell loading machine, a shell carrier, and coöperating but separate means automatically, substantially simultaneously,

and at one operation, to assemble shells ready for placing in said shell carrier, to place shells therein, and to close loaded shells therein.

55. In a shell loading machine, a shell carrier, and coöperating but separate means automatically, substantially simultaneously, and at one operation, to assemble shells ready for placing in said shell carrier, to place shells therein, and to discharge completed shells therefrom.

56. In a shell loading machine, a shell carrier, and coöperating but separate means automatically, substantially simultaneously, and at one operation, to assemble shells ready for placing in said shell carrier, to load shells placed therein, and to close loaded shells therein.

57. In a shell loading machine, a shell carrier, and coöperating but separate means automatically, substantially simultaneously, and at one operation, to assemble shells ready for placing in said shell carrier, to load shells placed therein, and to discharge completed shells therefrom.

58. In a shell loading machine, a shell carrier, and coöperating but separate means automatically, substantially simultaneously, and at one operation, to assemble shells ready for placing in said shell carrier, to close loaded shells therein, and to discharge completed shells therefrom.

59. In a shell loading machine, a shell carrier, and coöperating but separate means automatically, substantially simultaneously, and at one operation, to assemble shells ready for placing in said shell carrier, to place shells therein, to load shells therein, and to close loaded shells therein.

60. In a shell loading machine, a shell carrier, and coöperating but separate means automatically, substantially simultaneously, and at one operation, to assemble shells ready for placing in said shell carrier, to place shells therein, to load shells placed therein, and to discharge completed shells therefrom.

61. In a shell loading machine, a shell carrier, and coöperating but separate means automatically, substantially simultaneously, and at one operation, to assemble shells ready for placing in said shell carrier, to place shells therein, to close loaded shells therein, and to discharge completed shells therefrom.

62. In a shell loading machine, a shell carrier, and coöperating but separate means automatically, substantially simultaneously, and at one operation, to assemble shells ready for placing in said shell carrier, to load shells placed therein, to close loaded shells therein, and to discharge completed shells therefrom.

63. In a shell loading machine, a shell carrier, and coöperating but separate means

- automatically, substantially simultaneously, and at one operation, to assemble shells ready for placing in said shell carrier, to place shells therein, to load shells placed therein, to close loaded shells therein, and to discharge completed shells therefrom. 5
64. In a shell loading machine, a shell carrier, and coöperating but separate means automatically, substantially simultaneously, and at one operation, to assemble shells ready for placing in said shell carrier and to load completely shells placed therein. 10
65. In a shell loading machine, a shell carrier, and coöperating but separate means automatically, substantially simultaneously, and at one operation, to place shells in said shell carrier and to load completely shells placed therein. 15
66. In a shell loading machine, a shell carrier, and coöperating but separate means automatically, substantially simultaneously, and at one operation, to assemble shells ready for placing in said shell carrier, to place shells therein, and to load completely shells placed therein. 20
67. In a shell loading machine, a shell carrier, and coöperating but separate means automatically, substantially simultaneously, and at one operation, to assemble shells ready for placing in said shell carrier, to load completely shells placed therein, and to close loaded shells therein. 25
68. In a shell loading machine, a shell carrier, and coöperating but separate means automatically, substantially simultaneously, and at one operation, to assemble shells ready for placing in said shell carrier, to load completely shells placed therein, and to discharge completed shells therefrom. 30
69. In a shell loading machine, a shell carrier, and coöperating but separate means automatically, substantially simultaneously, and at one operation, to place shells in said shell carrier, to load completely shells placed therein, and to close loaded shells therein. 35
70. In a shell loading machine, a shell carrier, and coöperating but separate means automatically, substantially simultaneously, and at one operation, to place shells in said shell carrier, to load completely shells placed therein, and to discharge completed shells therefrom. 40
71. In a shell loading machine, a shell carrier, and coöperating but separate means automatically, substantially simultaneously, 45
- and at one operation, to assemble shells ready for placing in said shell carrier, to place shells therein, to load completely shells placed therein, and to close loaded shells therein. 50
- and at one operation, to assemble shells ready for placing in said shell carrier, to place shells therein, to load completely shells placed therein, and to close loaded shells therein. 55
72. In a shell loading machine, a shell carrier, and coöperating but separate means automatically, substantially simultaneously, and at one operation, to assemble shells ready for placing in said shell carrier, to place shells therein, to load completely shells placed therein, and to discharge completed shells therefrom. 60
73. In a shell loading machine, a shell carrier, and coöperating but separate means automatically, substantially simultaneously, and at one operation, to assemble shells ready for placing in said shell carrier, to load completely shells placed therein, to close loaded shells therein, and to discharge completed shells therefrom. 65
74. In a shell loading machine, a shell carrier, and coöperating but separate means automatically, substantially simultaneously, and at one operation, to place shells in said shell carrier, to load completely shells placed therein, to close loaded shells therein, and to discharge completed shells therefrom. 70
75. In a shell loading machine, a shell carrier, and coöperating but separate means automatically, substantially simultaneously, and at one operation, to assemble shells ready for placing in said shell carrier, to place shells therein, to load completely shells placed therein, to close loaded shells therein, and to discharge completed shells therefrom. 75
76. In a shell loading machine, a shell carrier formed of flat polygonal surfaces each of which is provided with a series of parallel rows of shell receptacles and having its center of gravity maintained in fixed position. 80
77. In a shell loading machine, the combination of a shell carrier, and means to co-operate with said shell carrier at different stations arranged around said shell carrier and adapted to place, load, and close a shell and deliver the same in completed form. 85

In testimony whereof, I hereunto affix my signature in presence of two witnesses.

HERBERT TALLEY.

Witnesses:

GEO. B. PITTS,
S. V. LOCKWOOD.
